[57] CLAIM

The ornamental design for a slide caliper, as shown and described.

DESCRIPTION

FIG. 1 is a perspective view of a slide caliper showing my new design;

FIG. 2 is a front elevational view thereof;

FIG. 3 is a rear elevational view thereof;

FIG. 4 is a plan view thereof from the top of FIG. 3;
FIG. 5 is a plan view thereof from the bottom of FIG. 3;

FIG. 6 is an end elevational view thereof from the right of FIG. 3;

FIG. 7 is an end elevational view thereof from the left of FIG. 3; and,

FIG. 8 is a view similar to FIG. 1 but showing the slide caliper with its jaws extended.

FIG. 1

FIG. 8

FIG. 2

FIG. 3

FIG. 4

FIG. 5

FIG. 6

FIG. 7
